UNITED STATES PATENT OFFICE.

FREDERIC E. GARDNER, OF BELOIT, WISCONSIN.

GRINDING MACHINE.

Application filed June 3, 1921. Serial No. 474,586.

This invention relates to grinding machines of the type known in the trade as disk grinders in which pieces or objects to be ground are passed between the opposed 5 grinding faces of annular grinding disks. The invention covers modifications and improvements in the construction, arrangement and operation over that of the machine in my copending application Serial 10 No. 472,977 filed May 27, 1921.

In the arrangement of this invention, two annular grinding disks are mounted opposite each other with their supporting spindles in axial alinement, and an important 15 object of the invention is to provide improved arrangement for supporting shields in the adjacent ends of the annular grinding disk apertures for preventing work parts from falling into the apertures from the carrier and also to guide such parts into and out 20 of the grinding fields. A further object is to so support the shields that they will automatically maintain their proper positions with reference to the grinding faces when 25 adjustment is made to compensate for wear on the grinding elements.

The above and other features of my invention are incorporated in the machine shown on the accompanying drawing, in 30 which drawing

Fig. 1 is an end elevational view,

Fig. 2 is a sectional view on plane 2—2 of Fig. 1,

Fig. 3 is a sectional view of the grinding structure, housings and carrier, on plane 35 3—3, Fig. 1, and

Fig. 4 is an end view showing the manner of supporting the shield suspending rods.

In the structure shown the machine base 40 10 supports at its opposite ends sub-base structures 11 and 12 on which are respectively mounted the carriers 13 and 14 for the annular grinding disks 15 and 16. The carriages 13 and 14 are of similar construction 45 and each is mounted on guideways 17 to be longitudinally shiftable or adjustable on the respective sub-base. Each has also journal boxes 18 for journaling the grinding wheel spindle 19 which between the journal boxes 50 carries the belt pulley 20 by means of which the spindle is rotated. At the inner end of each spindle is secured a head 21 in which is seated the respective grinding disk 15 or 55 16 as clearly shown in Fig. 2. The spindles are in axial alinement so that the grinding

disks are concentric with their grinding faces parallel.

The carriages are longitudinally adjustable on their sub-bases and means are provided for rapidly giving them a rough preliminary adjustment and for then giving them a final accurate adjustment. A screw shaft 21' is rotatable in the bracket 22 but is confined against longitudinal movement by the collars 23. The threaded end of the 60 shaft extends through the walls 24 and 25 on the carriage and between these walls the shaft receives the threaded hub 26 on which is the worm wheel 27 which is engaged by the worm 28 on the countershaft 29 which 65 is suitably journaled in walls of the carriage and which at its outer end has the hand wheel 29'. The outer end of the screw shaft is squared to receive a wheel or crank and when this shaft is thus turned the carriage 70 is comparatively rapidly shifted, the threaded hub being locked by the engagement of the worm wheel with the worm. For final adjustment the shaft 21' is held 75 against rotation and the wheel 30 is turned, 80 slow movement being then imparted to the carriage by virtue of the worm and worm wheel gearing. Adjustments can thus be rapidly and accurately made for the proper gap between the grinding faces.

The work carrier shown is in the form of a plate 30 extending transversely of the machine in a vertical plane between the grinding elements. At its ends the plate is secured on the uprights 31 and 32 extending 85 from the ends of the base 33 which is slidably mounted on the track structure 34 secured on the intermediate wall 34' of the base 10. Strips 35 secured to the underside of the base engage below the track flanges 90 36 to keep the base in proper alinement on the rail during reciprocation of the carrier. Near one end of the plate 30 of the holder is the opening or pocket 37 for receiving objects to be ground. With the arrangement shown the object is carried with the holder through the grinding field between the opposed annular grinding elements and is then carried back to permit removal of the object and insertion of another object. 95 Feeding and discharging of the objects from the carrier may be manually or automatically performed.

Provision must be made to separate the grinding elements sufficiently to permit pas- 100 105 110

sage therebetween of the unground objects. In the arrangement shown the sub-base structure 12 is fixed against longitudinal movement on the machine base, but the sub-base 11 is reciprocable on the machine base on ways 38. On the end of the machine base a bracket 39 journals a shaft 40 on which is the belt pulley 41. At its outer end the shaft carries a worm 42 which meshes 10 with the worm wheel 43 secured on one end of the shaft 44, this shaft being journaled in the bearing extension 45 on bracket 39 and in the bracket 46 on the machine base. At the other end of the shaft 44 is secured 15 the cam 47 which engages with the cam roller 48 at the lower end of the lever 49. Intermediate its ends the lever is pivoted on pin 50 supported in the bracket 51, and at its upper end the pin 52 pivots the lever 20 to the outer end of the sub-base 11. Between the lower end of the lever and the machine base is interposed a compression spring 53 which tends to swing the lever to cause the sub-base to shift inwardly. The 25 spring has the adjustable abutment 54 on the lever by means of which its compression force can be adjusted. The inward movement of the sub-base is limited by the stops 55 which are secured on the sub-base and 30 abut against the end of the machine base 10.

The contour of the cam 47 is such that its engagement with the cam roller will swing the lever to shift the sub-base 11 outwardly against the force of the spring 53, 35 and will then permit the spring to return the lever to gradually shift the carriage inwardly so that the grinding faces are gradually brought together after receiving an object whereby the object is gradually ground 40 to the degree desired, grinding stopping as soon as the stops 55 engage with the machine base. The grinding element 15 is thus positively shifted away from the element 16 but 45 yieldingly though forcibly returned by the power exerted by spring 53. The pin 50 on which the lever 49 is pivoted is preferably eccentric so that further adjustment may be made to obtain accurate movement of the sub-base 11.

50 The mechanism for reciprocating the work carrier is operated in timed relation with the retraction of the sub-base 11 to separate the grinding elements for the reception of work. On the shaft 44 which supports the worm 55 wheel 43 is also mounted a bevel pinion 56 which meshes with the bevel gear on the countershaft 57 on which countershaft is the gear pinion 58 which meshes with the idler gear 59 which engages the gear 59' on the horizontal shaft 60. The shaft 60 is journaled in bearings 61 and at its inner end has the crank arm 62 from which extends the crank pin 63 into the slot 64 of a gear sector 65 trunnioned at its lower end in the bearing 66. The sector gear meshes with a

rack 67 secured to the underside of the work holder base 33, the track 34 having the passageway 68 through which the sector extends.

The shaft 60 rotates in clockwise direction 70 (Fig. 1) and by virtue of the pin and slot connection shown a very desirable variable speed of travel is imparted to the work carrier. In the position of the parts shown in Fig. 1 the pocket 37 of the work carrier is 75 outside of the grinding elements ready to receive a piece of work to be ground. As the shaft 60 is now rotated, the crank pin 63 increases its distance from the axis of the gear sector and the carrier travels slowly to 80 carry the work into position between the overlapping grinding faces, and such slow movement continues while the work is being carried along between the faces so that ample time is given for thorough and efficient grinding. When the crank arm is in 85 vertical position the movement is the slowest and the work will be in the middle of the grinding field. When the crank arm passes the vertical position the crank pin starts to 90 travel downwardly in the slot and the speed of the work holder accelerates and such acceleration rapidly increases as the pin approaches the lower end of the slot, the result being that the ground piece of work is 95 rapidly carried back through and out of the grinding field, and as it leaves the field the sector radius again increases and the carrier movement is slowed up until it reaches its outermost position. At the end of its outer 100 stroke the carrier is practically at a standstill for a short period of time and ample opportunity is provided for inserting and adjusting a piece of work in the holding pocket. Just before a piece of work reaches 105 the grinding field to be ground the grinding elements are separated to receive the work, such separation being automatically accurately performed at the proper time by the mechanism already described. 110

The extent of swing of the gear sector 65 is such that the work carrier will be moved a distance to carry the pocket 37 with the work therein across the radial width of the grinding elements at that side of the machine. If desired, a second work holder pocket 68' may be provided in the plate 30 for carrying work between the grinding elements at the opposite side of the machine, it being thus possible to greatly increase the 115 capacity of the machine. Where only one pocket is used, only one retraction of the grinder carriage is necessary for each back and forth travel of the work carrier. However, if both sides of the machine are used, 120 then there should be two retractions of the grinder carriage for each back and forth travel of the carrier. This can be readily taken care of by the proper gearing relation 125 between the shaft 60 and the cam shaft 44. 130

With the two hole arrangement there will be a retraction of the grinding element 15 to receive work placed in the pocket 37 and while the work is traveling between the 5 grinding surfaces at that side of the machine, the grinding elements are pressed together to effect grinding. After the work in pocket 37 has been carried into the grinding elements the pocket 68 will be outside of 10 the grinding elements to receive a piece of work and when the carrier is moved in the opposite direction to carry this work toward the grinding element, the element 15 is again retracted so that the work in pocket 68' is 15 received between the grinding faces on the left side of the machine. While the work is being ground and carried to the inside of the grinding elements, the finished work in pocket 37 is carried out. Owing to the 20 crank pin and slot connection the gear sector 65 will shift the work carrier 30 more rapidly toward the left than toward the right (Fig. 1) so that grinding at the right side of the machine will be more rapid than that 25 at the left. However, for certain classes of work such rapid grinding is very desirable.

To assist in guiding objects into and out of the grinding fields, I provide guide plates 30 and 70 which are in line with the work receiving pockets and which may be supported from the hoods or housings 71 and 72 mounted on the sub-base structures 11 and 12 respectively. To prevent objects 35 from falling off the carrier into the apertures of the annular grinding disks and also to guide the objects when they are carried out of the grinding elements, I provide the shields 73 and 74 in the respective apertures adjacent the grinding faces. The shield 73 40 is supported at the inner end of the rod 75 which extends axially through the spindle 19 and is held against longitudinal movement by collars 76 on the rod at opposite sides of the arm 77 through which the rod 45 extends, the arm extending upwardly from the sub-base 11. The rod 78 which supports the shield 74 extends through the arm 79 on the sub-base structure 12 and is held against longitudinal movement by the collars 80. 50 The rods are free to rotate as at times the objects are partly between the grinding faces and partly between the shields. As the grinding disks are worn down by grinding operation and dressing operation, the carriages 13 and 14 are adjusted to compensate for such wear and the grinding faces are thus kept in proper alignment with reference to the shields. The shields cooperate with the guide plates to guide the objects accurately 55 with reference to the grinding fields as they are carried back and forth with the carrier.

Although the sub-base structure 12 is not 60 adjustable longitudinally on the machine base, it may be tilted on its horizontal axis

81 by means of jack screws 82, and the carriage 14 is adjustable on its vertical axis 83 by means of set screws 84. By means of this adjustment the grinding face of the disk 16 may be kept in true parallelism with the 70 grinding face of the element 15.

I claim as my invention:

1. In a grinding machine of the class described, the combination of a base, a carriage adjustable on said base, a spindle journaled 75 on said carriage, an annular grinding disk supported on one end of said spindle, a rod extending through said spindle, an arm extending from said base for supporting said rod, and a shield on said rod and engaging 80 in the grinding disk aperture.

2. In a grinding machine of the class described, the combination of a base, a carriage adjustable on said base, a spindle journaled 85 on said carriage, an annular grinding disk mounted on said spindle, a rod extending axially through said spindle, a shield at the inner end of said rod supported thereby within the grinding disk aperture, and means for preventing longitudinal 90 movement of said rod relative to said base.

3. In a grinding machine of the class described, the combination of a base, a carriage adjustable on said base, a spindle journaled 95 on said carriage, an annular grinding disk on said spindle, a work carrier movable in front of said disk to carry work into contact with the disk, a rod extending axially through the spindle, a shield on the inner 100 end of said rod for closing the grinding disk aperture, said rod being rotatable with said disk but being locked against longitudinal movement therewith.

4. In a grinding machine of the class described, the combination of an annular 105 grinding disk, a work carrier movable in front of said disk to support work to be ground, a supporting spindle for said disk, a rod extending axially through and being rotatable with said spindle, a shield on the inner end of said rod closing said disk aperture, and means for effecting relative adjustment between the grinding disk and shield.

5. In a grinding machine of the class described, the combination of an annular 115 grinding disk having an aperture, a work carrier movable in front of said disk and aperture, a shield closing said aperture at its outer end, and a supporting stem for said shield extending axially with reference to 120 said grinding disk.

6. In a grinding machine of the class described, the combination of a base, a carriage movable on said base, a spindle journaled on 125 said carriage, an annular grinding disk mounted on said spindle, means for adjusting said disk axially, a shield positioned within the disk aperture and substantially closing the same, and means extending into said disk supporting said shield, said last 130

mentioned means being unaffected by adjustment of said disk.

7. In a grinding machine of the class described, the combination of a base, a carriage 5 movable on said base, a spindle journaled on said carriage, an annular grinding disk mounted on said spindle, a rod extending

into the disk aperture, and a shield at the inner end of said rod supported thereby in the grinding disk aperture.

10

In testimony whereof, I have hereunto set my hand.

FREDERIC E. GARDNER.
